REGENERATIVE INGOT-HEATING FURNACE WITH OIL BURNERS

Filed May 23, 1947

UNITED STATES PATENT OFFICE

2,504,379

REGENERATIVE INGOT-HEATING FURNACE
WITH OIL BURNERS

Frederick Stuart Bloom, Mount Lebanon Township, Allegheny County, Pa.

Application May 23, 1947, Serial No. 749,949

3 Claims. (Cl. 263—15)

1

This invention relates to a regenerative furnace and, in particular, to the provision of oil burners in an ingot-heating furnace or soaking pit.

Ingot-heating furnaces are usually installed in banks, i. e., a plurality of heating chambers or pits are constructed side-by-side so as to be accessible to a common crane. If the furnaces are of the regenerative type, the checker chambers thus have to be placed at opposite ends of the heating chamber proper. The area above the checker chambers must be kept clear to permit removal of the furnace cover and to provide working space. These conditions are no obstacle to the supply of gaseous fuel which is usually delivered from the outer end of the checker chamber into a port or passage extending over the checkerwork and communicating with the heating chamber. It has not been feasible heretofore, however, to fire regenerative ingot-heating furnaces with liquid fuel because there is no place suitable for the installation of the necessary burners or atomizing nozzles and the pipe connections thereto.

In one type of prior installation where an attempt was made to use liquid fuel for ingot-heating furnaces, the burners were placed at the outer ends of the checker chambers and arranged to fire over the checkerwork. This caused deterioration of the roof of the checker chamber because of the excessive temperature created by mixture of the fuel and incoming hot air and the resulting combustion before the gases actually entered the heating chamber. In another type of installation, the burners were so located as to fire directly into the heating chamber through the entry port. With this arrangement, however, it is difficult to avoid burning or washing of the ingots by direct impingement of the flame thereon. In both these types of installation, extensive provisions have to be made for cooling the burners and piping. Because of the difficulties mentioned, it has generally been considered that prior attempts to utilize oil for firing regenerative ingot-heating furnaces have been failures.

I have invented a novel regenerative furnace suited for heating ingots or other purposes, so constructed as to permit the installation and operation of liquid-fuel burners without any of the above difficulties or objectionable results. In a preferred embodiment, I construct a well between the heating chamber and each checker chamber, communicating with the port leading from the checker chamber to the heating cham-

2

ber, and install an upwardly firing burner in each well. I supply liquid fuel and an atomizing agent such as steam to the burners and admit only enough air thereto for partial combustion in the well. The combustible mixture ascending from the well mixes with the hot air entering the heating chamber from the adjacent checker chamber. Thus combustion with a slow flame proceeds as the gases traverse the heating chamber, being about completed by the time they leave it and enter the other checker chamber on their way to the stack.

A complete understanding of the invention may be obtained from the following detailed description and explanation which refer to the accompanying drawings illustrating a preferred embodiment. In the drawings,

Figure 1 is a partial plan view, partly broken away, of a furnace having the invention incorporated therein;

Figure 2 is a vertical section taken along the plane of line II—II of Figure 1; and

Figure 3 is a cross section taken along the plane of line III—III of Figure 2.

Referring now in detail to the drawings which are largely diagrammatic, an ingot-heating furnace indicated generally at 10 comprises a heating chamber proper 11 provided with a removable cover 12 and adapted to receive ingots 13 for heating to rolling temperature. The bottom of the furnace is supported in the usual manner on structural members 11a resting on a suitable foundation. Ports 14 open into opposite sides of the chamber 11 providing communication between the latter and checker chambers 15 on opposite ends of the heating chamber. Each chamber 15 contains a mass of checkerwork 16 adapted to be connected alternately by suitable reversing valves and flues 17 to a source of air under pressure and a waste-gas stack.

The construction described so far is largely conventional and forms no part of my invention.

In order to permit the furnace 10 to be fired with liquid fuel such as oil, I provide a well 18 extending downwardly from the ports 14 between the heating chamber 11 and each of the checker chambers 15. The wells 18 are defined by the side walls of the heating chamber and cross walls

19 in the checker chambers. Inlets 20 open into the bottoms of the wells from the space between the checker chambers and below the heating chamber. Upwardly-firing burners 21 are disposed in the bottoms of the wells and are supplied with a mixture of steam and atomized fuel from mixing devices 22 to which steam and oil

are supplied by pipe lines 23. The inlets 28 have partitions 24 therein which limit the induction of air with the entering fuel.

Assuming that the furnace is being fired from left to right, air supplied through the flues 17 will pass upwardly through the left-hand mass of checker brick 16 which has previously been heated by waste combustion gases and absorb heat therefrom before passing to the heating chamber 11 through the port 14. The mixture of steam and oil discharged upwardly from the bottom of the left-hand well 18, after partial combustion in the well, meets the entering hot air in the port 14 and is thereby swept into the chamber 11. Combustion of the fuel proceeds slowly as the flame and combustion gases pass through the heating chamber toward the right-hand port 14 and thence through the other checker chamber to the stack. By restricting the air induced by the entering fuel, I limit the combustion which occurs in the well 18. Ordinarily, I prefer to admit to the well only about 20% of the air required for complete combustion of the fuel. This prevents the temperature in the well from increasing to a value at which the brickwork would deteriorate. As the ascending combustible mixture meets the entering hot air, it is directed by the latter into the heating chamber producing a slowly burning flame therein which does not injure the ingots because, as stated, combustion of the fuel is not completed until about the time the gases flow out through the right-hand port 14. The burners 21 being located at the bottoms of the wells, which are several feet deep, are protected from the entering hot air, the flame in the heating chamber and the combustion gases flowing out through the right-hand port to the stack.

It will be understood that the burners in the two wells are operated alternately, depending on the direction of firing. That is to say, after firing from left to right for the desired period, the left-hand burners are turned off and the right-hand burners are turned on simultaneously with the reversal of the flow of air and gases to and from the heating chamber.

It will be apparent from the foregoing that the invention makes possible the use of liquid fuel for firing regenerative furnaces, without any of the difficulties previously encountered. As a result of the location of the burners in the wells and the restriction of the air induced with the fuel, but little combustion occurs in the well. The fuel mixes with the entering air for further combustion at the mouth of the port so that the roof of the latter is not subjected to excessive temperature. The slowly burning flame which is thus produced in the heating chamber does not cause injury to the surfaces of the ingots by burning or washing. The location of the burners in wells avoids the necessity for special provisions to cool them. By limiting the combustion occurring in the well, the deposit of carbon is minimized.

Although I have illustrated and described but a preferred embodiment of the invention, it will be recognized that changes in the details of construction and operation may be made without departing from the spirit of the invention and the scope of the appended claims.

I claim:

1. A regenerative furnace for heating ingots by means of fuel oil, comprising an ingot heating chamber having ports at opposite ends thereof and a floor to support ingots, a checker chamber spaced from each of said ports, a conduit extend-

ing horizontally between each checker chamber and the adjacent port, a well opening into an intermediate portion of the conduit and having sides extending downwardly therefrom substantially below the level of the floor of the ingot heating chamber, a fuel oil burner mounted within the lower portion of each well directed to fire vertically upwardly, a fuel oil supply conduit extending into the well to the burner, means to supply fuel oil to the burner at a predetermined rate, an air inlet opening into each well adjacent the burner and means restricting the amount of air entering the well through said inlet, said restricting means being adjusted to limit the flow of air through said inlet to an amount which will support combustion of about 20% of the predetermined amount of fuel oil simultaneously supplied to the burner.

2. A regenerative furnace for heating ingots without melting them comprising an ingot-heating chamber having ports at opposite ends thereof, a checker chamber spaced from each of said ports, a main air passage connecting each checker chamber and the corresponding port, each main air passage having a portion opening into the corresponding port and extending with substantially uniform cross section straight toward the port, a well extending transversely of and opening into said portion of each of the main air passages, a fuel oil burner mounted in each well adjacent the end of the well opposite to its opening into the main air passage, and means to supply fuel oil to the burner, each well being open adjacent the burner to admit only sufficient air to the interior of the well to support partial combustion of said fuel oil within the well before it enters the air passage.

3. A regenerative furnace for heating ingots without melting them comprising an ingot-heating chamber having a floor to support the ingots and ports at opposite ends thereof, a checker chamber spaced from each of said ports, a main air passage connecting each checker chamber and the corresponding port, each main air passage having a portion opening into the corresponding port and extending horizontally with substantially uniform cross section straight toward the port, a vertical well opening into said portion of each of the main air passages, upwardly-firing fuel oil burners mounted in each well, the level of the top of the well being substantially above the level of the floor of the heating chamber and the level of all of the burners in the wells being substantially below the level of the floor of the heating chamber, and means to supply fuel oil to the burners, each well being open adjacent the burners to admit only sufficient air to the interior of the well to support partial combustion of said fuel oil within the well before it enters the air passage.
